UNITED STATES PATENT OFFICE.

FREDERIC AUMONIER, OF LONDON, ENGLAND.

DESIGN FOR WALL-PAPER.

SPECIFICATION forming part of Design No. 22,959, dated December 5, 1893.

Application filed October 20, 1893. Serial No. 488,753. Term of patent 3½ years. Registered in England March 3, 1893, No. 208,518.

To all whom it may concern:

Be it known that I, FREDERIC AUMONIER, (trading as WM. WOOLLAMS & Co.,) a subject of the Queen of Great Britain, and a resident 5 of 110 High Street, near Manchester Square, London, England, have invented a new and useful Design for Wall and Ceiling Paper, (registered in Great Britain on the 3d of March, 1893, No. 208,518,) of which the following is a 10 specification.

This design for wall and ceiling paper as represented by the accompanying drawing, consists of a center composed of two rings united by double lines arranged radially and 15 with a star like interior. Outside the outer ring is a series of scrolls with the united apexes alternately terminating in a kind of flame and bow knots. Around these is a wreath of leaves with a flower at intervals. From the 20 flame scrolled leaves lead to diamond shaped lines associated at one part by a ring, through which the stem of a flower and a leaf passes. Outside the foregoing arranged vertically and horizontal from the center are cornucopias 25 with their tails running into a splayed bundle of leaves, and with the heads looking upwardly and downwardly respectively the intervening parts between the heads being

filled in with a splayed leaf device, the apex of which appears in the hollow of the border scrolls of the foregoing device forming a center to the whole. The cornucopia and the splayed out leaves inclose a rectangular tablet, arranged horizontally and vertically respectively, and these are surrounded by lines with outwardly curved scrolls at the ends, and with inwardly curved scrolls from the sides the latter having a cluster of leaves with a band, the whole with the first device forming a kind of cross. The corners of the 30 cross are filled up with oppositely curved scrolls and splayed leaves, inclosing a Tudor rose with leaves as rays therefrom, and with splayed leaves to complete the corners. All the several parts above referred to constitute 35 40 45 an artistic square.

I claim—

The design for wall and ceiling paper substantially as herein shown and described.

The 10th day of March, 1893.

FREDERIC AUMONIER.
